HAND BAG FRAME

Jacob Schoenfeld, New York, N. Y.

Application September 1, 1934, Serial No. 742,377

18 Claims. (Cl. 150—29)

This invention relates to devices such as frames for portable receptacles or handbags.

One object of the invention is to provide a device having a frame channel clamped to secure bag material and a member closely overlying the material and/or the frame channel and so arranged and mounted in an improved manner on the frame channel as not to damage or impair the bag material or the frame structure and to permit rapid assembling of the device without obstructing insertion of the bag material or the clamping thereof in the frame channel.

Another object of the invention is to furnish a device having improved means for mounting an ornamental member and adapted for coordination with a fastening element; and another object of the invention is to furnish improved, novel fastening means and a mounting therefor.

The securing on frames of portable receptacles such as ladies' handbags of external ornamental devices disposed to closely laterally overlie the handbag or even the frame elements thereof, has heretofore been impossible where the frame elements used were channels in which the bag material was clamped. The reason for this is that the insertion of the bag material into the channels was obstructed, and likewise the channels were rendered difficult of convenient access for clamping.

The cheapest and most practical method for constructing ladies' handbags is by inserting the bag walls into frame channels and clamping the latter to secure the bag walls. Obviously the channel opening must be substantially free and unobstructed. If in the case, for example, of an inverted channel, a fastener, ornament or other member were rigidly affixed to the channel so as to overlie the same and a side of the handbag, it would be impractical to attempt to insert and clamp the bag material in the channel.

To overcome the foregoing difficulties, this invention provides a simple, practical arrangement for attaching such ornament, fastener or the like to the channel frame, without the necessity for soldering, riveting, or the like which would damage the handbag material, the frame or both, the means provided by this invention desirably permitting manipulation by the same clamping tools as are used for clamping the frame channels on the handbag frame.

It is noteworthy that the bag manufacturer purchases the handbag frames from a frame manufacturer, who must supply frames that are as completely assembled as possible, and to which the bag material can be attached simply

and conveniently to produce neatly finished uniform handbags without requiring extra operations such as soldering, or the like, above referred to. This invention fulfills these objects and requires merely the making of a deformation which is quickly and easily effected as by ordinary hand tools, and which does not require the bag manufacturer to carry special tools or devices.

A further object of the invention is the provision of a device of the class alluded to which shall have the advantages mentioned, and which shall consist of relatively few and simple parts, and be inexpensive to manufacture, durable, reliable, and efficient in use.

A still further object of the invention is to furnish an improved method for rigidly securing a member to a handbag frame where the member would otherwise obstruct insertion of bag material into the frame.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a fragmentary isometric view showing a device embodying the invention.

Fig. 2 is an enlarged fragmentary side view thereof.

Fig. 3 is a vertical sectional view taken on line 3—3 of Fig. 2.

Fig. 4 is an enlarged fragmentary horizontal cross sectional view showing a clamped deformed engagement of parts.

Fig. 5 is an isometric view of an element of the invention in separated position.

Fig. 6 is a fragmentary isometric view with parts in section showing a modification of the invention.

Fig. 7 is a similar view of another modification of the invention as used with regular channel.

Fig. 8 is a similar view of still a further modification of the invention as applied to inverted channels.

Fig. 9 is a diagrammatic view showing a method for practising the invention.

Fig. 10 is a fragmentary end view of the device shown in Fig. 6.

showing a further modification of the invention.

The advantages of the invention as here outlined are best realized when all of its features and instrumentalities are combined in one and 5 the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred 10 exemplification of the invention.

Referring in detail to the drawing, 10 denotes 15 a device embodying the invention. The same may include one or more frame elements for portable receptacles, and may illustratively be embodied in the conventional inverted U-shaped channel frames 11, 12 such as are used in ladies' handbags, and which may be pivotally interconnected as at 13 for movement toward and away 20 from each other to close and open the handbag.

Hangbag material or walls 14 such as leather, cloth or the like conventionally have marginal portions 15 inserted into the channels, which are 25 then clamped thereon, with the walls 14 overlying the outer walls 16 of the channels. The clamping of the channels may be effected in the usual manner, as by tightly pressing the outer and inner flanges 16, 17, 18 of each channel toward each other to slightly deform the channel 30 and cause the same to strongly clamp the handbag wall.

19 denotes a device, member or ornament which is mounted on the channel 12 so as to 35 closely overlie the top or outer flange 16 thereof, or the adjacent handbag material 14, or any combination thereof. For example, the device 19 may include one or more members 20 of generally angular shape, each having a horizontal portion 21 to extend outwardly over its supporting channel, and an upright portion 22 to extend downward in close proximity to the adjacent handbag wall 14. Desirably the device 19 is 40 mounted on the inner flange 18 in such manner as not to interfere with the tight closing of the frame channels, nor to mar the uniformity thereof at the inner flange face.

With the device 19 thus mounted and arranged 45 it is clear that the handbag wall could not be inserted and clamped in the frame channels, because the device 19 obstructs the opening of the channel frame. It would be necessary to cut an opening in the handbag wall for the 50 passage therethrough of the device 19. This would cause the cost of manufacture of the handbag to be prohibitive.

Accordingly I have conceived that an easily 55 attachable fastening device may be used, which may or may not be releasable, but which primarily assures rigidity and accessibility so that the device 19 may be conveniently mounted, and be secured in a strong, reliable manner. Another desirable factor is that the same or similar tools may be used, so that a simple clamping 60 movement may be used for securing the device in position. Neatness, and compactness are necessarily important.

Broadly, I utilize a means which may be operated by a slide motion for a strong frictional 65 engagement which, in its final character, is permanent. The clamping action, if used, assures easier initial engagement and a stronger final connection.

Accordingly, I provide means including a guide 70 or T-bar or rail element that may be mounted on

or connected to the flange 18, preferably internally of the channel 12, as by soldering the flange 23 to the flange 18. The head 24 of said rail may lie a suitable distance above the top of the frame channel, and may extend parallel to the latter for any desired distance along the horizontal section 5 of the frame channel.

The device 19 may include a grooved member 25 of any suitable character adapted to endwise slidably receive and engage the rail head 24. 10 The member 25 may consist of a strip of metal rolled or pressed into channel shape, with the back thereof soldered to the under plane faces 26 of the members 20, thereby securing the same rigidly, with the device 19 forming a unit. 15

A movable element or associated ornamental device 27 may be of any suitable construction and is desirably of generally similar appearance with the members 20. The element 27 may be hingedly mounted at 28 on the channel 11, one 20 leaf 29 of the hinge being secured to the inner flange 17 as shown. The element 27 is adapted to be snugly slidably fitted between the members 20, and may have a stepped portion 30 to engage over the grooved member 25, and an offset at 31 25 to clear the adjacent handbag fabric 14. The element 27 aids in securely holding the device 19 against longitudinal movement in the closed position of the handbag, when stresses occur on the lock.

The manner of manufacturing the invention will now be described. It will be understood that the frame channels 11, 12 are completely assembled with the guide bar 24, and the member 27 secured thereon as in final form. This structure, 35 together with the unit 19, is supplied to the bag assembler, who clamps the bag to the channel frames as usual, and then applies the unit 19, and finally clamps the unit in place by means of a pair of pliers 32, as shown in Fig. 9. The rail 40 head 24 may be slightly narrowed or deformed as shown at 33, the member 25 being correspondingly deformed as shown at 34, so that these elements have registering deformations that prevent removal of the unit 19. The member 27 in 45 closed position engages the section 34 to hold the handbag closed, and thus conceals the deformed part of the unit 19.

In use, the device 10 is opened by swinging the member 27 upward and away from the channel 50 12 to release the latter. To close the device, the member is swung into the position shown in Fig. 3.

The invention is capable of being embodied in 55 highly attractive designs, as shown.

In Fig. 6 is shown a device 35 embodying a modification of the invention. According to this device, the frame channel 12 having the guide rail provided with the head 24 as hereinbefore described, may initially slidably receive a grooved 60 or channeled element 36, after the bag material 14 has been clamped in the frame channel. The element 36 may then be clamped or pinched on the rail head 24 in any suitable manner, as, for example, by clamping the element 36 at its extreme ends where sufficient expansibility is had or by upwardly deforming the lip or flange 37 to bind against the rail head. The element 36 as well as the guide rail may be of any suitable length, and said element 36 may carry an ornamental device which may comprise a top flange 38 to overlie the channel 12 and a side flange 39 to overlie the adjacent handbag fabric 14. It is thus seen that the pivotal device may be secured to the inverted channel in closely overlying rela- 70 75 75

tion thereto and to the handbag wall without obstructing the insertion of the latter and the clamping thereof in the frame channel.

Instead of clamping the element 36 to the head 24, or supplemental thereto, the element or the member 38, as shown, may have a lip 38a at each end thereof, which lips initially project outward in the plane of member 38. These lips are bendable downward as shown in Fig. 10, so as to prevent removal of the element 36 from the rail head 24.

In Fig. 7 is shown a device 40 as embodying another modification of the invention with particular application to the regular channels 41, 42, as distinguished from inverted channels. The channel 41 may have its outer wall 42 provided with a longitudinal downward extending projection 43 which may be in the nature of a plate having a flange 44 secured to the flange 42 interiorly of the channel. The plate 43 may have a rail element or head 45 extending in parallelism to the channel 41 and at a suitable distance therebelow. The plane of said head may be inclined at an angle to the vertical as shown for a purpose hereinafter described. Desirably the plate may have an intermediate portion 46 slightly inwardly offset so as to leave free the edge portion 47 of the flange 42. A member or ornamental device 48 which may, for example, be in the nature of

a plate may have projecting from its rear face a groove or channel portion 49 adapted to initially slidably engage the head 45, and an angle element 50 adapted by the same movement of the device 48 to engage the free edge portion 47 between the latter and the offset portion 46. Thus it is seen that the member 48 may be anchored to the channel 41 along two horizontal lines vertically spaced from each other and adapted for engagement by a single movement of the member, where one of the anchorages has the capacity of affording a positive lock. Such positive locking action may be obtained by subjecting the elements 45 and 49 to a clamping operation as hereinbefore described, these elements being accessible by pressing the handbag wall 51 laterally away from the elements to a sufficient degree to permit insertion of a pair of pliers or other tool. By reason of the downward spacing of these elements below the channel 41, the handbag wall will have sufficient flexibility to laterally yield, and as a result of the downwardly inclined relation of these elements, the channel part 49 may be readily gripped by a tool inserted between the handbag and the plate 48. The structure may be finished and rendered wholly neat in appearance by the provision of a longitudinal top lip 52 for lateral external abutment with the flange 42.

In manufacturing the device 40, the handbag walls are inserted into the frame channels and the latter clamped in the usual manner. Thereafter the member 48 is applied as hereinbefore mentioned and the elements 45 and 49 clamped together whereupon the entire handbag is complete.

In Fig. 8 is shown a device 53 according to a still further modification of the invention. This device may include a plurality of inverted channels 54, 55 from one of which at the inner flange thereof extends an upwardly projecting plate structure 56 which is reversely bent upon itself as shown so as to afford a top flange 57 that extends longitudinally of and parallel to the frame channels and substantially equally overlies adjacent parts thereof. The ornamental device 58 may be of angular shape and may have a top

flange portion 59 insertable into the grooved or channel structure 56 so that upon clamping the latter the device 58 is rigidly and reliably mounted. This clamping operation can be conveniently performed when the frame channels 54 and 55 are moved away from each other. In all other respects the structure and manner of operation may be the same as hereinbefore described.

In Fig. 11 is shown a further modification of the invention, wherein a device 60 and the channel 61 thereof, otherwise alike in all respects with the device 19 and channel 25 thereof, respectively, may have an indentation or depression 62 formed therein intermediate of the members 20 and along the center line of the top or back of the channel 61, said indentation being engageable, resiliently or otherwise in a hole 64 formed in the rail head 65. The latter corresponds to the rail head 24, and said hole may be directly above the flange 66 of the rail head. In practise the indentation 62 may be formed only after the device 60 is applied to the rail head, after which a suitable tool may be applied to form the indentation in alignment with the hole 64.

The term clamping is intended to apply to the modes of securing dovetail elements against separation from each other as shown in Figs. 6 and 11 as well as in the other embodiments of the invention.

It will be appreciated that various changes and modifications may be made in the device as shown in the drawing, and that the same is submitted in an illustrative and not in a limiting sense, the scope of the invention being defined in the following claims.

I claim:

1. A handbag including a downwardly opening frame channel, handbag material clamped in said frame channel, one flange of the frame channel having a downwardly projecting rail element extending longitudinally therewith, a device positioned externally of the handbag and having a channel element for initially slidably engaging said rail element, said channel element being clamped into permanent engagement with the rail element, said elements being disposed between the handbag material and said device and being accessible by pressing the handbag material laterally away from said device.

2. A handbag including a downwardly opening frame channel, handbag material clamped in said frame channel, one flange of the frame channel having a downwardly projecting rail element extending longitudinally therewith, a device positioned externally of the handbag and having a channel element for initially slidably engaging said rail element, said channel element being clamped into permanent engagement with the rail element, said elements being disposed between the handbag material and said device and being accessible by pressing the handbag material laterally away from said device, said device having a portion disposed above the channel element and slidably engaged with an edge portion of the said flange of the frame channel.

3. A frame for portable receptacles, including a plurality of inverted channel members movable toward and away from each other for opening and closing the receptacle, said channel members being adapted to be clamped on bag material inserted therewith for securing said material, with the latter overlying the outer flanges of the channel members, a headed rail element adjacent to the inner flange of one channel member and being connected to the channel member there-

- within with the head of the element external of and above the channel member, a fastening element connected to the other channel there-
within in proximity to the inner flange thereof,
5 a member disposed at a side of the receptacle in overlying relation to the adjacent bag material, said member having a grooved deformable portion adapted for slidably engaging the rail head, said grooved portion extending endwise
10 from said member so as not to be obstructed thereby and being clamped to irremovably engage the rail head, and the fastener element being movable to engage over said endwise extending grooved portion for releasably holding the
15 frames together and concealing the clamped part of the grooved portion, as set forth.
4. A frame for portable receptacles, including a plurality of inverted channel members movable toward and away from each other for opening and closing the receptacle, said channel members being adapted to be clamped on bag material inserted thereinto for securing said material with the latter overlying the outer flanges of the channel members, a headed rail element adjacent to the inner flange of one channel member and secured therewith with the head of the element external of and above the channel member, a fastening element connected to the inner flange of the other channel member, a plurality of members disposed at one side of the receptacle in overlying relation to the adjacent bag material, a channel fastener on which said members are mounted in overlying relation to the adjacent bag material, said channel fastener being adapted for slidable engagement with said rail head, said members being spaced from each other along the channel fastener and the latter including a portion extending between said members, said portion being clamped on the rail head
30 to prevent sliding detaching movement of the channel fastener, said fastening element being movable for guiding engagement between said members and for releasable engagement with said clamped portion to hold the receptacle closed, as set forth.
5. A frame for portable receptacles, including a channel member in which a bag wall is adapted to be secured by clamping the channel member, an element closely overlying the channel member so that it obstructs the insertion of bag material into the channel member and means for connecting said element to the channel member, said means including slidably interengaging rail and groove portions on the channel member and the element, said portions consisting of relatively thin deformable sheet material so that the groove portion can be manually clamped on the rail portion in non-sliding relation thereto to secure the element to the channel member, whereby said element can be rigidly secured to the channel member after the bag wall is clamped therein so as not to obstruct the insertion of the bag wall into the channel member.
6. A frame for portable receptacles, including an inverted channel member in which a bag wall is adapted to be secured by clamping the channel member, an element, and means for connecting said element to the channel member, said means including slidably interengaging dovetailed male and female portions of deformable material on the channel and element, said female portion having a thin wall adapted to be manually rigidly clamped on the male portion, said portions having mating deformations to cause the rigid interengagement, said element lying closely above

the channel member and one of said portions being secured to the channel member therewithin, as set forth.

7. A frame for portable receptacles including an inverted channel member in which bag material is adapted to be secured by clamping the channel member, with the bag material overlying a flange of the channel member, a headed rail element having a flange and a head extending therealong, said flange being secured in the channel member and projecting upward with the rail head disposed externally of the channel member, said element and the head thereof being positioned adjacent to the second flange of the channel member and being spaced from the first mentioned flange thereof so that the bag material can be inserted into and clamped in the channel member, and a member closely overlying the channel member so as to obstruct access thereto and having a groove adapted for initial slidable dovetail engagement with the said rail head, said member being of a thin deformable sheet metal adapted to be manually clamped on the rail head to permanently secure the member to the channel without affecting the bag material, and said member and rail head having registering opposite lateral deformations to prevent release of the member from the rail head.

8. A frame for portable receptacles including an inverted channel member in which bag material is adapted to be secured by clamping the channel member, with the bag material overlying a flange of the channel member, a headed rail element connected to the channel member therewith so as to extend longitudinally adjacent to the second flange of the channel member and to project with the head thereof external to the channel member, said rail head being disposed in overlying relation to the second flange along a plane spaced sufficiently above the channel member so that the bag material can be inserted into and clamped in the channel member and a sheet metal member adapted to be mounted on the channel member, said member having a downward opening groove for initially slidably engaging the rail head, said member being of a deformable material so that it can be clamped on the rail head without obstruction by the channel member and bag material for permanently securing the member to the channel member, said member projecting laterally to closely overlie the channel member and adjacent bag material.

9. A handbag including a frame, an ornament, and means for mounting the ornament on the frame so as to closely overlie adjacent handbag material, said frame being adapted for the securing of the said material in the frame, and said means including two preformed elements individually connected to the respective frame and ornament, one of said elements being a channel element and the other a rail, said elements being adapted for slidably interengaging each other, said elements being deformable, and one of the elements consisting of a thin deformable sheet material clamped on the other element to prevent separation of the elements, whereby the ornament can be mounted after the bag material is secured in the frame.

10. A handbag including an inverted channel in which handbag material can be secured by clamping the channel thereon, and means for mounting a device on the channel in closely overlying relation to said material the insertion of which into the channel would have been otherwise obstructed by said device, said means includ-

ing interrelatively movable dovetailed male and female elements, one of said elements having a recess and the other element having a projection engaged in said recess to prevent said movement, whereby the device can be mounted on the channel after the bag material has been secured therein.

11. A handbag including an inverted channel in which handbag material can be secured by clamping the channel thereon, and means for mounting a device on the channel in closely overlying relation to said material the insertion of which into the channel would have been otherwise obstructed by said device, said means including elements having slidable dovetail interengagement with each other, one of the elements having end lugs bent to engage the ends of the other element to prevent separation of the elements from each other, so that the device can be permanently secured to the frame after the bag material has been clamped therein.

12. A frame for portable receptacles including a plurality of channel members movable toward and away from each other for opening and closing the receptacle, said channel members being adapted to be clamped on bag material inserted thereinto, a headed rail element secured to one of the channel members with the head of the element external of and above its channel member, a member disposed at a side of the receptacle in overlying relation to the adjacent bag material, said member having a grooved portion of deformable material adapted for slidably engaging the rail head, said grooved portion extending endwise from said member and being deformed to permanently engage the rail head, and a fastening element connected to the other channel member and being movable into receptacle closing position over said endwise extending grooved portion for releasably holding the channel members together, as set forth.

13. A frame for portable receptacles including a plurality of channel members movable toward and away from each other for opening and closing the receptacle, said channel members being adapted to be clamped on bag material inserted thereinto, one of the channel members having a headed rail element secured thereto and extending along the inner flange of the channel member with the head of the rail element external of the channel member so as not to obstruct the latter for insertion of the bag material, a device having one portion overlying the opening of said channel member and a second portion extending along the outer flange of the channel member so that the device obstructs the channel member against insertion of the bag material thereinto, and means for connecting said device with said rail element, including a second element adapted for detachable snug dovetail engagement with said rail head to permit insertion of the bag material into said channel member without obstruction by said device, and a portion of thin easily deformable material for interengaging the elements to prevent the same from being detached, whereby the device can be permanently rigidly mounted on the frame in course of the manual assembling of the receptacle and without soldering or other operations that can damage the bag material.

14. A frame for portable receptacles including a plurality of inverted channel members movable toward and away from each other for closing and opening the receptacle, said channel members being adapted to be clamped on bag material in-

serted thereinto with the bag material dependingly overlying the outer flanges of the channel members, a device having one portion overlying one of the channel members and a second portion extending along the outer flange of the said channel member so as to obstruct the insertion of the bag material into said channel member, and means for rigidly mounting said device on said channel member, said means including one element rigidly connected to said channel member so as to extend along the inner flange thereof and a second element rigidly connected to said device, said elements being adapted for snug detachable dovetail interengagement, whereby the device is removable for insertion of the bag material into said channel member, and said means including a portion consisting of a deformable material so as to be movable for interengaging the elements to prevent removal of the device, whereby said receptacle can be completely assembled manually without damage to the bag material.

15. A frame for portable receptacles including a plurality of inverted channel members movable toward and away from each other for closing and opening the receptacle, said channel members being adapted to be clamped on bag material inserted thereinto with the bag material dependingly overlying the outer flanges of the channel members, a device having one portion overlying one of the channel members and a second portion extending along the outer flange of the said channel member so as to obstruct the insertion of the bag material into said channel member, and means for rigidly mounting said device on said channel member, said means including one element rigidly connected to said channel member so as to extend along the inner flange thereof, and a second element rigidly connected to said device, said elements having snug interfitting male and female interengagement and including preformed portions to prevent any relative movement between the elements in one direction, and one of said elements having a deformable portion for interengaging the elements against any movement relative to each other in a direction substantially at right angles to the first mentioned direction, whereby said receptacle can be completely manually assembled without damage to the bag material.

16. A frame for portable receptacles including a plurality of inverted channel members movable toward and away from each other for closing and opening the receptacle, said channel members being adapted to be clamped on bag material inserted thereinto with the bag material dependingly overlying the outer flanges of the channel members, a device having one portion overlying one of the channel members and a second portion extending along the outer flange of the said channel member so as to obstruct the insertion of the bag material into said channel member, and means for rigidly mounting said device on said channel member, said means including one element rigidly connected to said channel member so as to extend along the inner flange thereof, and a second element rigidly connected to said device, said elements having snug interfitting male and female interengagement and including preformed portions to prevent any relative movement between the elements in one direction, and said means including a part movable for interengaging the elements against any movement relative to each other in a direction at right

angles to the first mentioned direction, as set forth.

17. A frame for portable receptacles including a plurality of inverted channel members movable 5 toward and away from each other for closing and opening the receptacle, said channel members being adapted to be clamped on bag material inserted thereinto with the bag material dependingly overlying the outer flanges of the channel members, a device having one portion overlying 10 one of the channel members and a second portion extending along the outer flange of the said channel member so as to obstruct the insertion of the bag material into said channel member, and means for rigidly mounting said device on said channel member, said means including one element rigidly connected to said channel member so as to extend along the inner flange thereof, and a second element rigidly connected to said device, said elements having snug interfitting 15 male and female interengagement, one of the elements having a recess portion in a side thereof, the other element having a projecting portion extending into said recessed portion, one of said portions consisting of a substantially easily deformable material for snug interengagement of the portions, and the element having the recessed portion having also a lip extending along said side at the recessed portion for interengaging the elements.
18. A frame for portable receptacles including a plurality of inverted channel members movable toward and away from each other for closing

and opening the receptacle, said channel members being adapted to be clamped on bag material inserted thereinto with the bag material dependingly overlying the outer flanges of the channel members, a device having one portion overlying 5 one of the channel members and a second portion extending along the outer flange of the said channel member so as to obstruct the insertion of the bag material into said channel member, and means for rigidly mounting said device on said channel member, said means including one element rigidly connected to said channel member so as to extend along the inner flange thereof, and a second element rigidly connected to said device, said elements having snug interfitting 10 male and female interengagement, one of the elements having a recess portion in a side thereof, the other element having a projecting portion extending into said recessed portion, one of said portions consisting of a substantially easily deformable material for snug interengagement of the portions, and the element having the recessed portion having also a lip extending along said side at the recessed portion for interengaging the elements.

JACOB SCHOENFELD.
